US00D832709S

(12) **United States Design Patent** (10) **Patent No.:** **US D832,709 S**
Cheng et al. (45) **Date of Patent:** **** Nov. 6, 2018**

(54) **BOTTLE**

(71) Applicant: **PepsiCo, Inc.**, Purchase, NY (US)

(72) Inventors: **Hai Shuo Cheng**, Shanghai (CN);
Gloria Chou, Shanghai (CN); **Patrick J. Finlay**, New Fairfield, CT (US);
Jennifer Te-Hsin Antczak, Darien, CT (US); **Susie Wang**, Shanghai (CN)

(73) Assignee: **PepsiCo, Inc.**, Purchase, NY (US)

(**) Term: **15 Years**

(21) Appl. No.: **29/596,600**

(22) Filed: **Mar. 9, 2017**

Related U.S. Application Data

(63) Continuation of application No. 29/525,469, filed on Apr. 29, 2015, now Pat. No. Des. 784,144.

Primary Examiner — Dana Meyrow

(74) *Attorney, Agent, or Firm* — Sterne, Kessler, Goldstein & Fox P.L.L.C.

(57) **CLAIM**

The ornamental design for a bottle, as shown and described.

DESCRIPTION

FIG. 1 is a top, front, left perspective view of a bottle showing the claimed design;

FIG. 2 is a front view thereof;

FIG. 3 is a right side view thereof;

FIG. 4 is a rear view thereof;

FIG. 5 is a left side view thereof;

FIG. 6 is a top view thereof; and,

FIG. 7 is a bottom view thereof.

The dashed broken lines in the figures show portions of the bottle that form no part of the claimed design.

The dot-dash broken lines in the figures show boundaries that form no part of the claimed design.

1 Claim, 6 Drawing Sheets
